FIRE DOOR CONSTRUCTION

Filed Feb. 14, 1927

INVENTOR
RUSSELL C. MAHON

BY

Russell C. Mahon
ATTORNEY.

UNITED STATES PATENT OFFICE.

RUSSELL C. MAHON, OF DETROIT, MICHIGAN, ASSIGNOR TO THE R. C. MAHON COMPANY, OF DETROIT, MICHIGAN, A CORPORATION OF MICHIGAN.

FIRE-DOOR CONSTRUCTION.

Application filed February 14, 1927. Serial No. 168,022.

This invention relates to fire door construction and the object of the invention is to provide a fire proof door in which a glass panel is mounted and which is so constructed as to prevent passage of fire from one room to another.

Another object of the invention is to provide a fire door in which the door frame is sheathed in metal and the glass panel is supported in metal so that no inflammable surface is exposed.

Another object of the invention is to provide a fire door in which the supporting members for the glass panel are concealed beneath a metal moulding which is secured to the door.

Another object of the invention is to provide a fire door in which the sheathing for the door frame is brought inwardly to provide a support for the glass panel.

These objects and the several novel features of the invention are hereinafter more fully described and claimed and the preferred form of construction by which these objects are attained is shown in the accompanying drawing in which—

Fig. 1 is an elevation of a fire door embodying my invention.

Fig. 2 is an enlarged section taken on line 2—2 of Fig. 1.

As shown in Figs. 1 and 2 the top and bottom rails and the stiles of the door are sheathed in a sheet metal casing 1. As shown in Fig. 2 the edges of the sheathing are brought out into the space for the door panel to provide a metal flange 2 consisting of a double thickness of the metal sheathing. A 16 gauge metal plate or strip 3 is spotwelded to this flange and the spotwelding secures the two thicknesses of metal sheathing together thus making the flange 2 permanent and sealing the wood stiles and rails within the sheathing. The flange 2 and the strip 3 are provided with spaced apertures for the bolts 4 which are utilized to secure the glass panel 5 in the door. In order to secure this glass panel in place a removable metal filler strip 6 is provided which is apertured to receive the bolts 4 and a removable plate or strip 7 overlaps the edge of the glass panel 5 and is also apertured to receive the bolts 4. By tightening the bolts 4 the glass panel is held between the metal strip 7 and the sheathing flange 2 and the metal

strip 3 is utilized to back up and stiffen the sheathing flange 2. When the door and panel have been assembled in this manner two sheet metal moulding strips 8 and 9 are positioned about the edge of the panel opening and are sweated to the adjacent parts of the door frame to conceal the panel supporting arrangement as will be readily understood from Fig. 1. The glass panel 5 may be of any type of glass desired but is preferably a glass which resists breakage by heat such as a wire reinforced glass or a laminated glass panel. With this arrangement the wood frame of the door is entirely sheathed in metal and by spotwelding through the double thickness flange 2 the wooden door frame members are sealed from any possible contact with flame in case of fire.

From the foregoing description it becomes evident that the device is very simple and efficient in operation, provides an arrangement whereby the door is entirely fireproof and provides a device which accomplishes the objects described.

Having thus fully described my invention, its utility and mode of operation what I claim and desire to secure by Letters Patent of the United States is—

1. In a fire door, a door frame formed of wooden rails and stiles, a sheet metal sheathing covering the rails and stiles, the edges of the sheathing being bent outwardly at a right angle and brought to parallel relation to provide a flange extending into the panel space of the door, a stiffening strip fitting into the right angle bend on one side of the flange, the stiffening strip and parallel portions of the flange being spot welded together to maintain the right angle bend and close the sheathing, a clamping strip, a spacing member between the clamping strip and the said flange fitting into the right angle bend on the side of the flange opposite the stiffening strip, a glass panel positioned between the clamping strip and the said flange, the stiffening strip, flange, spacing member and clamping strip being provided with a series of apertures, a series of bolts extending through the said apertures and clamping the parallel flange portions between the spacing member and stiffening strip and clamping the glass panel between the flange and the clamping strip, a sheet metal moulding secured to one side of the door frame

- sheathing and concealing the clamping strip, and a sheet metal moulding secured to the other side of the door frame sheathing and concealing the stiffening strip and flange.
- 5 2. In a fire door, a door frame formed of wooden rails and stiles, a sheet metal sheathing covering the rails and stiles, the edges of the sheathing being bent outwardly at a right angle and brought to parallel relation
- 10 to provide a flange extending into the panel space of the door, a stiffening strip fitting into the right angle bend on one side of the flange, the stiffening strip and parallel portion of the flange being spot welded together
- 15 to maintain the right angle bend and close the sheathing, a clamping strip, a spacing member between the clamping strip and the said flange fitting into the right angle bend on the side of the flange opposite the stiffening strip, a glass panel positioned between the clamping strip and the said flange, the stiffening strip, flange, spacing member and clamping strip being provided with a series
- 20 of apertures and a series of bolts extending through the said apertures and clamping the parallel flange portions between the spacing member and stiffening strip and clamping the glass panel between the flange and the clamping strip.
- 25 3. In a fire door, a door frame formed of wooden rails and stiles, a sheet metal sheathing covering the rails and stiles, the edges of the sheathing being brought to the panel side of the door frame and bent outwardly at

a right angle to parallel relation to provide 35 flange portions extending into the panel space of the door, a stiffening strip fitting into the right angle bend of one flange, a spacing member fitting into the right angle bend of the other flange, the stiffening strip 40 and said flanges being spot welded together to seal the sheathing, a clamping strip engaging against the spacing member, a glass panel positioned between the clamping strip and the flange portions, and means for bindingly securing the clamping strip, and spacing member to the flange portions and stiffening strip.

4. In a fire door, a door frame formed of 45 wooden rails and stiles, a sheet metal sheathing covering the rails and stiles, the edges of the sheathing being bent at a right angle and brought to parallel relation to provide a flange extending into the panel space of the door, a stiffening strip fitting into the right 50 angle bend on one side of the flange, the stiffening strip and parallel portions of the flange being spot welded together to maintain the right angle bend and to seal the sheathing, a clamping member detachably 55 secured to the said flange and stiffening strip, and a glass panel adapted to be secured between the clamping member and the said flange.

In testimony whereof I sign this specification.

RUSSELL C. MAHON.
